UNITED STATES PATENT OFFICE.

THOMAS HENRY CLARKE, OF NEWARK, NEW JERSEY, ASSIGNOR TO SHIRLEY MANUFACTURING CO., OF SHREVEPORT, LOUISIANA, A FIRM CONSISTING OF MEYER A. FREEDMAN AND DAVID MENDELSON.

DESIGN FOR A RING.

Application filed January 4, 1923. Serial No. 4,809. Term of patent 7 years.

To all whom it may concern:

Be it known that I, THOMAS H. CLARKE, a citizen of the United States, and a resident of Newark, county of Essex, State of New Jersey, have invented a certain new, original, and ornamental Design for a Ring, of which the following is a specification, reference being had to the accompanying drawing, forming part thereof.

The figure is a perspective view of my new design for a ring.

I claim:

The ornamental design for a ring, substantially as shown.

THOMAS HENRY CLARKE. [L. s.]
